RAZOR BLADE EDGE ALIGNING DEVICE

Vaino Jarvi, New York, N. Y.

Application March 13, 1940, Serial No. 323,781

9 Claims. (Cl. 51—158)

This invention relates to new and useful improvements in a razor blade edge aligning or perfecting device or crystal strop.

More specifically, the invention proposes the construction of a device for sharpening or preserving the cutting edges of razor blades of the Gillette type or other double edged or single edged blades, and characterized by a base having a smooth concave top surface and provided with a means arranged in a manner to cause the cutting edges or edge of the blade to be disposed at right angles to the length of a concave top surface or arranged to hold the blade concave to act on a straight surface.

Still further it is proposed to provide a means for pivotally mounting the said means in a manner to swing in an arc concentric with the curvature of the concave top surface so as to cause the cutting edges of the razor blade to be sharpened while being moved across the concave top surface with its cutting edges arranged accurately at right angles to the length of the concave top surface.

Another object of this invention proposes to characterize the holding means by a handle extending from the base and which carries a bar on its bottom end and which is accurately arranged at right angles to the concave top surface in a manner to be engaged into the centrally disposed slot formed in the razor blade to dispose the blade as hereinbefore described.

Still further it is proposed to provide the bottom end of the handle with a member arranged to engage the top face of the razor blade immediately behind its cutting edges to urge the cutting edges into face contact with the concave top surface of the base.

Still further it is proposed to provide the bottom end of the handle with a means for imparting a slight curvature to the razor blade in a manner to cause the cutting edges to be more accurately seated upon the top surface of the base.

For further comprehension of the invention, and of the object and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a razor blade edge aligning device constructed in accordance with this invention.

Fig. 2 is a plan view of Fig. 1.

Fig. 3 is a vertical sectional view taken on the line 3—3 of Fig. 2.

Fig. 4 is a view similar to Fig. 3 but illustrating the handle and its bottom member in a raised position.

Fig. 5 is an enlarged detailed view of a portion of Fig. 1.

Fig. 6 is a side elevational view of the bottom portion of the handle.

Fig. 7 is a view similar to Fig. 3 but illustrating a modification of the invention.

Fig. 8 is a perspective view of the top blade holding member.

Fig. 9 is a perspective view of the bottom blade holding member.

Fig. 10 is a perspective view of the handle and its respective parts used in the form of the invention similar to Fig. 7, but illustrating a still further modification.

Fig. 11 is a vertical sectional view, illustrating another modification of the device.

The razor blade edge aligning device, according to this invention, includes a base 10 having a smooth concave top surface 10^a. This base 10 is preferably constructed of glass, plastics or any similar material capable of being polished to a high finished surface. Upwardly extending walls 10^b continue from the body portion of the base 10 and extend completely around the concave top surface 10^a and are arranged for the purpose of maintaining lubricating fluids within the concave top surface. This lubricating fluid should preferably be water, but it may also be oil or any other similar fluid for aiding the movement of a conventional razor blade across the concave top surface. A razor blade 11 of the Gillette type or any other double edged or single edged blade which has a centrally disposed slot 11^a which extends parallel to its cutting edges 11^b is adapted to be placed upon the concave top surface 10^a with its cutting edges arranged substantially at right angles to the length of the concave surface.

A handle 12 extends radially from the concave top surface 10^a. The handle 12 is formed with a slot 12^a which extends longitudinally thereof. The bottom end of the handle carries a bottom member 16. This bottom member 16 is formed with upwardly extending lugs 13 which extend along opposite sides of the bottom end of the handle 12. Pins 14 are engaged through the lugs 13 and into the handle 12 for pivotally supporting the bottom member 16 on the handle. The bottom member 16 is arranged to have its side edges 16^a engage the top face of the razor blade 11 immediately behind its cutting edges 11^b. The

member 16 acts to urge the bottom of the cutting edges 11^b of the razor blade into face contact with the top surface of the base 10.

A bar 17 is horizontally supported upon the bottom end of the handle 12 beneath the bottom face of the member 13. This bar 17 has a rod 18 extending upwards therefrom. The rod 18 has a square cross section and extends through a square throat opening 19 formed in the bottom end of the handle 12. The inner end of the rod 18 has a head 18^a located within an enlarged opening 12^a formed in the handle and continuing from the throat opening 19. The relationship between the handle 12, the bar 17 and the rod 18 is so accurately formed that the bar 17 extends exactly at right angles to the length of the concave top surface 10^a of the base. This bar 17 is adapted to be passed through the slot 11^a formed in the razor blade 11, as shown in Figs. 3 and 4, for causing the cutting edges 11^b of the blade 11 to be extended exactly at right angles to the length of the concave top surface 10^a.

A shaft 20 is extended horizontally through the slot 12^a formed in the handle 12. An arm 21 is provided, which has its bottom end mounted on one side wall of the base 10. The bottom end of the arm 21 is provided with a vertically extended elongated slot 22 through which a screw 23 passes. This screw 23 is embedded in the material of the upwardly extending wall 10^b of the base 10. A thumb nut 24 is engaged upon the screw 23 for clamping the arm 21 into face contact with the wall of the base 10. The wall of the base 10 on opposite sides of the arm 21 is provided with integrally formed outwardly extending lugs 25. One edge of the arm 21 is provided with a plurality of serrations 26 which are adapted to engage complementary serrations 27 formed upon the adjust lug 25 for preventing relative vertical movement of the arm 21. By loosening the thumb nut 24 and moving the arm 21 outwards on the screw 23 to disengage the serrations 26 and 27 it is possible to move the arm 21 either upwards or downwards as desired, whereupon it is adapted to be returned to its starting position for fixedly holding the same in its newly adjusted position.

The arm 21 extends upwards from the base 10 and has its free end bent at right angles to assume a position parallel to the concave surface 10^a. A yoke 21^a is turnably mounted on the free end of the arm 21 and has its arms extending along opposite sides of the handle. The free ends of the shaft 20 are fixedly attached to the ends of the arms of the yoke 21^a.

A resilient means acts between the top face of the bottom member 16 and the shaft 20 for urging these parts in opposite directions. This resilient means is in the form of a spring 28 which operates between the top face of the member 16 and the shaft 20 for urging the bottom member 16 against the top face of the razor blade 11. In view of the fact that the shaft 20 extends through the slot 12^a formed in the handle 12 it is possible for the handle to move downwards relative to the shaft 20 as caused by the expansion of the spring 28 to permit the bottom member 16 to engage the top face of the razor blade 11.

The operation of this form of the invention is as follows:

For sharpening the cutting edges of a razor blade it is merely necessary to manually raise the handle 12 to similarly raise the bottom member 16 against the holding action of the spring 28 to the position shown in Fig. 1. The force of gravity will cause the bar 17 to remain in face

contact with the concaved top surface 10^a of the base 10. The bar 17 is then also raised to permit the blade 11 to be sharpened to be engaged therebeneath. The bar 17 is again lowered and caused to pass into the slot 11^a of the blade 11. Due to the fact that the slot 11^a extends parallel to the cutting edges 11^b and the bar 17 extends exactly at right angles to the length of the concaved top surface 10^a the blade 11 will be turned into a position in which the cutting edges will be exactly at right angles to the length of the concave top surface 10^a and the device will be in the position illustrated in Fig. 4.

The handle 12 is again released and the tension of the spring 28 will cause the handle 12 to move downwards on the shaft 20 to cause the edges 16^a of the member 16 to engage the top face of the razor blade 11 immediately behind its cutting edges 11^b. The pivotal mounting of the member 16 will permit it to turn into a position in which it will be accurately seated on the blade 11. The device is then in the position shown in Fig. 3 and ready for sharpening the blade which is accomplished by manually grasping the top end of the handle 12 and moving the same backward and forwards to pivot the handle about the shaft 20 and cause the blade to be moved across the face of the base 10 to sharpen the cutting edges. After being moved across the concaved top surface 10^a several times, the blade 11 is again released and turned around and positioned beneath the member 16 to permit the other side of the cutting edges 11^b to be sharpened.

In the modification of the invention shown in Figs. 7 and 10 the construction of the aligning device is similar to that previously described, except for the provision of a means for imparting a slight curvature to the blade 11 relative to a flat top surface 10^{aa} found on the base 10. To accomplish this an inverted U-shaped yoke 29 is pivotally attached to the bottom end of the handle 12 by means of lugs 13' and pins 14'. The intermediate arm 29^a is pivotally attached to the handle 12 intermediate of its ends and the side arms 29^b extend downwards from the intermediate arm 29^a.

The bottom member consists of a pair of superimposed members 16' and 16''. The razor blade 11' is adapted to be engaged between the adjacent faces of these members 16' and 16'' as shown in Fig. 6. Due to the fact that the members 16' and 16'' have a slight curvature they will impart the same curvature to the blade 11'. The bottom member 16' is provided with outwardly extending trunnions 30 which are adapted to engage complementary openings 31 formed in the downwardly extending side arms 29^b of the yoke 29.

The yoke 29 is formed of slightly flexible material for permitting the free ends of the downwardly extending side arms 29^b to be spread apart to permit the trunnions 30 to be engaged and removed from the openings 31. This form of the invention is also provided with a means for causing the cutting edges 11^b of the razor blade 11' to be extended at a desired angle to the length of the concave top surface 10^{aa} of the base 10. This means comprises an integrally formed upwardly extending bar 17' formed on the top face of the bottom member 16'. This bar 17' is adapted to pass through the opening 11^a in the blade 11' and into a complementary opening 17'' formed in the top member 16''. A screw 32 carrying a washer 33 is adapted to be engaged into the bar 17' for locking the top member 16'' and the razor blade 11' in position on the bottom member 16'.

In other respects this form of the invention is similar to the previous form.

In Fig. 10, the bottom member 16''' is curved opposite to the upper member 16'' for holding the razor blade in a position which permits the rotation of same about trunnions 30, so that either member 16'' or 16''' may be at the top.

In the form of the invention shown in Fig. 11 the bottom member 34 is so arranged that it tends to impart a slight curvature to the razor blade 11'' so that it may be moved across the flat surface 10^{aa} of the base member 10. The bottom member 34 is formed with a pair of spaced upwardly extending lugs 35. These lugs 35 are adapted to extend along opposite sides of the bottom end of the handle 12. Pins 36 are passed through the lugs 35 and into the bottom end of the handle 12 for pivotally supporting the bottom member upon the bottom end of the handle 12.

The bottom face of the bottom member 34 has a downwardly extending projection 34^a which continues into an integrally formed bar 34^b which is adapted to engage the slot 11^a in the blade 11''. This bar 34^b is arranged exactly at right angles to the length of the flat surface 10^{aa} and is adapted to turn the razor blade 11'' so that its cutting edges 11^b will be exactly at right angles to the length of the flat surface 10^{aa}. A screw 37 is threadedly engaged into the bottom of the bar 34^b and securely holds the blade in position on the bottom member 34. The bottom face of the bar 34^b is arranged slightly higher than the free edges of the member 34 and when the screw 37 is tightened in position it tends to draw the razor blade 11'' into its curved position. In other respects this form of the invention is similar to the previous form.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft.

2. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, said base being formed of glass, plas-

tics or other similar material capable of being polished to a high finished surface.

3. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a rod extending from said bar and having a square cross section and engaging a similarly shaped throat opening extended inwards from the bottom end of said handle to cause said bar to be accurately extended at right angles the length of the concave top surface of said base to cause the cutting edges of said razor blade to be similarly extended.

4. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a rod extending from said bar and having a square cross section and engaging a similarly shaped throat opening extended inwards from the bottom end of said handle to cause said bar to be accurately extended at right angles the length of the concave top surface of said base to cause the cutting edges of said razor blade to be similarly extended.

5. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, said resilient means comprising a spring coaxially mounted on said handle and acting between said shaft and the top face of said bottom member.

45

6. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, and means for adjustably mounting the bottom end of said arm upon the side of said base member.

50

7. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a yoke turnably mounted on the free end of said arm, said yoke having the free ends of its arms engaging opposite sides of said handle and said shaft having its free ends fixedly attached to the free ends of said arms.

55

8. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a yoke turnably mounted on the free end of said arm, said yoke having the free ends of its arms engaging opposite sides of said handle and said shaft having its free ends fixedly attached to the free ends of said arms.

60

9. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a yoke turnably mounted on the free end of said arm, said yoke having the free ends of its arms engaging opposite sides of said handle and said shaft having its free ends fixedly attached to the free ends of said arms.

65

10. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a yoke turnably mounted on the free end of said arm, said yoke having the free ends of its arms engaging opposite sides of said handle and said shaft having its free ends fixedly attached to the free ends of said arms.

70

11. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, a yoke turnably mounted on the free end of said arm, said yoke having the free ends of its arms engaging opposite sides of said handle and said shaft having its free ends fixedly attached to the free ends of said arms.

75

engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, said bottom member being pivotally mounted on the bottom of said handle and urged by said resilient means into a position in which its edges will engage the top face of said razor blade immediately in back of its cutting edges.

8. A razor blade edge aligning device, comprising a base having a smooth concaved top surface, a handle extending radially of said concaved surface and having a bottom member for engaging a razor blade and a shaft engaging through said slot in said handle, resilient means acting between said shaft and said bottom member for urging these parts in opposite directions,

and an arm mounted on said base and supporting said shaft, said bottom member comprising a pair of superimposed members between which the razor blade is adapted to be disposed, and said members being formed with a complementary arch for similarly arching said razor blade.

9. A razor blade edge aligning device, comprising a base having a smooth concaved top surface, a handle extending radially of said concaved surface and having a bottom member for engaging the top face of a razor blade and also having a longitudinally extending slot, a bar supported on the bottom of said handle and adapted to engage in a slot in said razor blade, a shaft engaging through said slot in said handle, resilient means acting between said shaft and said bottom member for urging these parts in opposite directions, and an arm mounted on said base and supporting said shaft, and means on said bottom member for imparting a slight curvature to said razor blade and including a holding screw.

VAINO JARVI.
